UNITED STATES PATENT OFFICE.

MAX KRAUSS, OF PHILADELPHIA, PENNSYLVANIA.

TALKING-MACHINE.

1,341,751.

Specification of Letters Patent.

Patented June 1, 1920.

Application filed December 13, 1919. Serial No. 344,622.

To all whom it may concern:

Be it known that I, MAX KRAUSS, a subject of the King of Bavaria, having resided in the United States for two years last past 5 and having declared my intentions of becoming a citizen thereof, residing in the city and county of Philadelphia, State of Pennsylvania, have invented a new and useful Talking-Machine, of which the following is 10 a specification.

My invention relates to the general class of talking or sound-reproducing machines which play records in the form of flat disks, both single and double faced, and it embodies 15 certain improvements upon a talking machine invented by and patented to me under date of September 26th, 1916, as No. 1,199,192, and further relates to another invention of mine in talking machines patented to me under date of January 14th, 1919, as No. 1,291,027, and still further relates to another talking machine invented by me and patented to me under date of 20 January 14th, 1919, as No. 1,291,556.

25 All of the foregoing machines are of the character employing a plurality of records any one of which may be selected to be played by any typical soundbox and stylus,—the general character of the machines 30 being best understood by a reference to the first of the foregoing patents, namely, No. 1,199,192, in which the general organization of a machine which my present invention also comprehends is disclosed and explained.

35 In the second of my patents above referred to, namely No. 1,291,027, the features of invention have special relation to means for applying and removing the records, while in the last of my patents, No. 40 1,291,556, the invention relates more particularly to special means for moving and controlling the tone arm and its soundbox with relation to any one of the plurality of records which the machine is adapted to 45 play.

My present invention while embracing the salient features of my former invention referred to, has special relation, first, to a novel means of controlling and operating 50 the tone arm and sound box relatively to any selected record, and, second, to a means for independently operating a selected record without at the same time operating any of the other records of the plurality of 55 which the selected record constitutes but one.

This last feature is one which my present invention especially relates to, because it is my principal object to simplify the construction and utilize less motive power by 60 making it possible to revolve but one record at a time.

With the foregoing and other objects in view, my present invention comprehends not only such a means as the foregoing of operating one record at a time, but also special constructions of the devices by which not only such operating of but one record is effected, but also such control of the tone arm and soundbox is afforded as makes the operation both accurate and efficient.

Special devices embraced in the construction of both the connective mechanism between the motor or source of power and of the controlling devices of the tone arm and sound box, are included in my invention and hereinafter described, a typical embodiment of a good construction being disclosed in the accompanying drawings, which illustrate an embodiment adding to the efficiency 80 of certain of the features which the inventions of my former patents include.

For a clearer understanding and differentiation of the features of importance which my present invention embodies, reference is 85 to be made to my prior patents, the present application representing only so much of a talking machine as is necessary to an understanding of the novel features.

My present machine, like those previously 90 patented to me, is adapted for use with any form of soundbox the stylus of which can operate either upon the up-and-down tone groove of the type of the "Edson", or the in-and-out groove of the type of the 95 "Victor", machines, only one sound box being necessary to enable the operator to at will select and play any one of any desired number of records which have been set up in my machine.

The machine, moreover, is capable of being operated by any preferred type of motor, whether mechanical or electrical.

In the accompanying drawings:

Figure 1 represents a top plan view of a 105 talking machine embodying my invention.

Fig. 2 represents a fragmentary front elevation of the front face of the casing with the slots through which the operating handle passes.

Fig. 3 represents in side elevation detached from the casing a portion of the tone arm,

100

110

the horn carrier and the elbow member of said carrier, the operating handle which lifts and drops the tone arm, and the swing lever which operates in consonance with the 5 operating handle to swing the tone arm laterally.

Fig. 4 represents a sectional plan on the dotted line 4—4 of Fig. 3,—the view being especially designed to illustrate the rocking 10 frame 45 and its connections with the swing bar 51.

Fig. 5 represents an end elevational view of the cross bar construction which serves as a compound joint for the connection of 15 the inner end of the tone arm with the elbow member of the horn carrier.

Fig. 6 represents a plan view, sectional on the line 6—6 of Fig. 3, of the operating handle, illustrating also the swing lever.

20 Fig. 7 represents a sectional end elevation through the operating handle, on the line 7—7 of Fig. 6.

Fig. 8 represents a fragmentary, internal, side elevational view, partly sectional, on 25 the line 8—8 of Fig. 1, illustrating the upper and the lower compartments of the cabinet, a record, the tone arm, the horn carrier, and the supporting and operating devices which connect my transmitting driving 30 mechanism with the horn carrier.

Fig. 9 represents a central, vertical, sectional detail on the line 9—9 of Fig. 8, through the record clamping devices, and parts of their operating means.

35 Fig. 10 represents a view similar to Fig. 9, sectional on the line 10—10 of Fig. 8, through the basal operating gearing by which in conjunction with the transmitting mechanism, any selected record is revolved.

40 Fig. 11 represents a fragmentary side elevation of a clamping spring plate device which I employ in conjunction with the fixed record clamping plates to hold the records in position.

45 Fig. 12 represents a front elevational view on the line 12—12 of Fig. 8, of the assemblage of records, their driving means and the transmission devices by which motion of revolution to the records is imparted 50 to said driving means.

Fig. 13 represents a fragmentary side elevational view, sectional on the line 13—13 of Fig. 12, of my transmission gearing.

55 Fig. 14 represents a side elevational view on the line 14—14 of Fig. 12, of the gearing connective of the driving shaft with the motor shaft.

Fig. 15 is a fragmentary perspective of the connecting lever 64, which is interposed 60 between the swing lever and its adjunctive connection with the swing bar of the tone arm.

Fig. 16 is a fragmentary detail of a stopping mechanism which I find it convenient 65 to employ.

Similar numerals of reference indicate corresponding parts.

Referring to the drawings:—

1 designates a cabinet or casing of any preferred character, material and dimensions, which by means of a horizontal partition 2 is divided into two hollow interior compartments, the upper of which I designate 3 and the lower 4.

5 designates the front face of the casing 75 through slots in which the operating handle is as hereinafter explained extended outwardly within reach of the operative.

6 designates a circular record-carrying plate of slightly larger diameter than a 80 circular aperture 18 in the partition 2. This plate embodies a plurality of transversely extending parallel record slots 7 through which in the assemblage of the parts, the lower segmental portions of the records extend, as shown in Figs. 8 and 12. The records are designated 8 and the sound grooves in them 12.

9 designates the tone arm, the numeral being applied to the body portion of said 90 tone arm or that portion which extends between the outer end to which the soundbox 10 is applied and the inner end where a jointed or swiveled connection hereinafter described is made between the tone arm and 95 an elbow member 13 extending above and an elbow member 13 extending above and being a part of a horn carrier 14, from the lower end of which a horn 15, see Fig. 8, extends. This elbow member is connected with and supported and carried by a traveling carrying plate 16 which travels upon the rods 19 extending longitudinally of the partition in the casing and in parallelism with the axis of the hubs which carry the records.

17 designates a slot in the partition 2 10 through which the horn carrier extends downwardly into the lower compartment 4 of the casing. So far as already described, my machine, as will be best understood by reference to it, embodies elemental features 110 included in my patents referred to.

The tone arm operating mechanism.

Inasmuch as in the operation of my machine it is necessary to impart both an up-and-down or a lifting and dropping movement to the tone arm to raise the soundbox clear of all the records and to move it down into place between any two of the plurality of records so that its stylus will play upon one of them, I have found it convenient in order to effect the lift and drop and the lateral swing of the tone arm, to resort to the following devices:—

To unite the inner end of the tone arm 125 with the upper horizontally-extending outer end of the elbow member 13, I connect these two parts by a compound joint of the following construction:—

Referring to Fig. 5,—21 designates a 130

cross bar secured by pivot pins 22 to the free outer end of the elbow member, as shown in Fig. 4, and pivotally connecting the inner open end of the tone arm with a right-angled cross bar 23, preferably integral with the cross bar 21 and at its outer ends carrying pivots 24 which pass through pivot apertures 25 in the tone arm. This construction, which is best illustrated in Figs. 4 and 5, permits, as is obvious, of an up-and-down movement of the tone arm upon the cross bar 21 as an axis, and a side-for-side or swinging movement of said tone arm upon the cross bar 23 as an axis.

Inasmuch as sound could escape through this compound joint unless it were prevented, I encompass both the inner end of the tone arm and the outer end of the elbow member of the horn carrier with an envelop 26 of cylindric form and composed of sheep skin or other preferred pliable and sound-proof material, which I rigidly secure to the tone arm conveniently by a collar 27 and by a clamping nut 28 internally threaded to embrace the externally threaded outer end of the elbow member so as to fasten the envelop, as will be understood by reference to Fig. 4.

The handle mechanism.

29 designates what I term the operating handle, the same being a lever having bifurcated ends 30 which encompass the elbow member 13 and are pivoted to it at 31, see Fig. 6. The extremities of the operating handle are connected by a cross link 32 from which depends a connecting link 33, for a purpose hereinafter explained. A spring 34 connects an outer end of the operating handle with the traveling carrying plate 16 so as to tend normally to maintain the operating handle in its upper position, as shown in Fig. 3.

As will be observed from Fig. 6, the outwardly extending handle end of the operating handle 29, or that which as shown in Fig. 8 extends through slots in the front face 5 of the casing, is a bent bar, the side plates of which, to which the numeral 29 is also applied, are spaced apart a sufficient distance to leave between them a longitudinal slot 35 within which is entered the fulcrum end 36 of what I term the swing lever 37, the function of which lever, through its connections now to be explained, is to effect the side-for-side swing of the tone arm, whereas the movement of the operating handle through connections later on explained effects the up-and-down movement of said tone arm.

This swing lever is pivoted at 38 to the side plates 29 of the operating handle, as seen in Fig. 3, so that the lever upon these pivots as a fulcrum, can be depressed by

pressure upon a thumb knob 39, against the resisting tendency of a spring 40 which bears against a shoulder 41 on its under face to hold it up to occasion the elevation of what I call a lifting toe 42 on its inner end, which toe in turn makes contact with the ball shaped bottom end of a lifting bar 43 pivoted at 44 to the outer end of a rocking frame 45, see Figs. 3 and 4, which is bent to encompass the elbow member 13 of the horn carrier and locked by the squared end 46 of one of the pivot pins 22 of the cross bar 21 by a clamping screw 47, see Fig. 4, which passes through a squared socket 48 on the inner end of a carrying plate 49 to the outer end of which is pivotally jointed upon a vertical rod 50 the inner end of a swing bar 51, the outer end of which is fastened at 52 to the tone arm.

Apart from any other movement, it will be understood that when the swing lever 37 is depressed and its lifting toe held in contact with the enlarged lower end of the lifting bar 43, and that when, the swing lever being held in such position, the operating handle 29 is depressed,—the tone arm will be elevated through the rocking frame 45, the carrying plate 49 and the swing bar 51.

It will be further understood that when the operating handle and swing lever are released, the tone arm will be free to be again raised into operative starting position.

The balancing of the tone arm in given positions I effect by the employment of a counterbalance weight 53, preferably stayed for vertical movement by being bored as at 54 and seated as to its bore upon a bracket 55,—which by a link or chain 56 is connected with the outer end of the rocking frame 45, as illustrated in Fig. 3.

Beneath the operating handle and pivoted to it at 57 is a swinging side plate 58, which lies flatwise against the outer side of the operating handle, as seen in Figs. 3, 6, and 7,—is bent under the handle with an under bend 59, through which the pivot 57 passes,—and is bent away from the handle to form a contact lug 60 held normally against the side of the operating handle by a spring 61.

Extending inwardly through a slot 62 in the side of the handle is an angular cam pin 63 against which the shoulder 41 of the swing lever 37 is adapted, in the deflection of said swing lever, to bear, and to be forced outward so as to force the contact lug 60 away from the operating handle.

When the swing lever 37 is in its elevated position, the swinging side plate 58 and its outwardly extending contact lug 60 occupy the positions shown in full lines in Fig. 6, and when the swinging lever is depressed occupy the positions indicated in dotted lines in said figure.

The object of forcing out the contact lug 60 in the manner described, is to cause it by bearing against the inner end plate 65 of a connecting lever 64 to turn said lever upon 5 a vertical pivot 66 passing through a lug 67 fast upon or connected with the elbow member 13, see Figs. 3 and 15. The outer end of this connecting lever is formed with a slot 68 through which passes what I call 10 a twisting pin 69 formed on the lower end of a vertical rod 50 by which the swing bar 51 is connected with the carrying plate 49,—see Fig. 3.

The twisting pin 69 is locked fast to the 15 lower end of this vertical rod 50, and to the upper end of the rod is locked the inner end of the swing bar 51, so as to fasten said bar upon the carrying plate 49 and at the same time permit of the movement of said 20 bar with the twisting pin 69 when the latter is turned or twisted by the throw of the connecting lever 64 as already explained.

The return of the twisting pin 69 and the swing bar 51 is effected by a spring 70 coiled 25 about the vertical rod 50 to one end of which said spring is connected while its other end is fastened to the carrying plate 49.

The inner end of the swing bar 51 is formed with a notched shoulder 71, see Fig. 30 4, which bears against a stop pin 72 on the upper face of the carrying plate 49, the office of which is to prevent the uncontrolled throw of the tone arm, and in consequence 5 of the stylus, against a record.

35 The swing lever 37, controls the side-for-side or lateral movement of the tone arm in the manner already described, and the operative effect of the coiled spring 70 acting through the twisting pin 69 upon the connecting lever 64, is to balance or oppose such 40 movement by a reverse action upon the swing lever 37 through the swinging side-plate 58, the contact lug 60 and said connecting lever 64.

45 *The slot and notch control.*

Through the front face 5 of the casing 5 extends, as stated, a longitudinal slot 73 through which extends as best shown in 50 Fig. 8, both the outer end of the operating handle and the thumb knob end of the swing lever.

The operating handle, as is usual in devices of this character, is adapted to be 55 moved by the operator longitudinally of this slot 73 to move the tone arm into placement with the desired record and with a selected vertical slot 74, within which the up-and-down movement of the operating handle 60 takes place.

Each of these vertical slots is notched or stepped at its side, in the form shown in Fig. 2, into two notches, 75 for a ten-inch record and 76 for a twelve-inch record. Of 65 course, other notches for records of lesser

diameter than ten inch or greater diameter than twelve inch may be formed in the vertical slots.

Intervening each vertical notch and formed as a part of the front face and in a sense together forming the upper line or boundary of the longitudinal slot 73, are a series of what I term stop blocks 77 against which in its longitudinal movement the operating handle may be brought to bear so as to hold it down for the stopping of the rotation of the records.

These vertical notched slots are disclosed in my Patent No. 1,291,556, as operative in connection with the selector arm and lever 80 latch of the machine of that patent and are not involved with my present invention except in so far as they serve in connection with the stoppage of the record motive mechanism.

The record motive mechanism.

As already explained, my present invention provides means for operating each of the records independently of every other record of the series or groups. My object in this particular is to relieve the motor of the duty of rotating all of the records simultaneously, which necessarily adds to the expense of operating the talking machine because of the additional power required.

To the foregoing end, each record is directly connected with an independent motive mechanism of the following preferred character:—

78 designates shaft-carrying bars assembled and supported by and between a longitudinally extending connecting rod 79 and the strips 80, see Figs. 1, 8, 12 and 13, between record-slots 7 in the record-carrying plate 6.

These shaft-carrying bars 78, one of which is used in connection with each pair of record-clamping devices hereinafter described, are each provided with an upper 110 housing 81, see Fig. 9, for the driven gearing of the record-carrying plates 82, and with a lower housing 83, see Fig. 10, for the driving gearing connective of what I term the record-driving shafts 84 with 115 the transmission mechanism hereinafter described.

As a reference to Figs. 9, 10, and 13 will best illustrate, within the upper housing 81 of each shaft-carrying bar 78 is housed in 120 suitable bearings 85 a separate record-carrying shaft 86, which carries a driven bevel spur wheel 87 engaging with a driving bevel pinion 88 on the upper end of the driving shaft 84.

Upon this shaft 86,—and as each of the series is a duplicate of every other I will describe only one,—is fastened the plate 82, which is the fixed member of the record-clamping device, and is of a diameter pref- 130

erably not exceeding that of the smallest records to be played and conveniently in the form of an apertured disk, which, as is obvious, rotates with the shaft 86 under the 5 actuation of the bevel gearing 87, 88.

This record shaft 86, see Fig. 9, projects beyond its housing 81 in both directions, so that upon the left-hand it forms a stub end directly designated by the number 86, and 10 upon the other or right-hand end is formed with a circular groove 89, into which is adapted to enter the angularly faced, semi-circular jaw 90 of a spring-controlled thumb latch 91, pivotally connected at 92 to the 15 hub 93, see Fig. 9, of a tubular outwardly extending collar 94, which is adapted to slip over the grooved right-hand end of the shaft 86 and be clamped thereto by the action of the jaw 90 when entered within the 20 groove 89.

This hub 93 is formed or connected with a plurality of radially extending clamping spring plates 95, see Fig. 11, which in the movement of the parts are adapted to press 25 against the face of the record opposite to that which lies against the clamping plate 82, to retain the record fixedly for rotation upon and with the shaft 86.

The movement of the latch 91 referably 30 to its pivot 92 is controlled by the spring 96 and the stop 97, as shown in Fig. 11.

It is evident that by manually moving the latch 91 endwise to the right in Fig. 9, the hub 93, collar 94, and spring plates 95, 35 which together constitute the moving member of the record-clamping mechanism, can be moved to the right, the collar 94 slipping over the left-hand end of the right-hand adjoining shaft 86 to the position shown in 40 dotted lines in Fig. 9, so as to afford a clearance for the introduction of the record upon the left-hand adjoining shaft 86, and its fastening against the clamping plate 82, when the hub, collar and spring plates are 45 moved to the left, as shown in full lines in Fig. 9, and so as to permit of the clamping of the jaw 90 into the groove 89 on said shaft 86.

The rotation of the selected shaft 86 to 50 rotate its record, is induced through the bevel gearing 87, 88, by the rotation of the driving shaft 84, which extends downwardly through a bearing 98 in the lower housing 83 and is rotated through the driven 55 bevel pinion 99, which is in mesh with the driving bevel spur wheel 100 fixed upon a stub shaft 101 suitably mounted in bearings 102, see Fig. 10, in the lower housing 83.

Upon the stub shaft 101 is mounted a 60 driven spur wheel 103, which, when rotated, will obviously impart rotation through the stub shaft 101 and the bevel gearing 100 and 99 to the selected record-driving shaft 84.

65 This entire last named assemblage of

driving elements is best illustrated in Fig. 10, and inasmuch as there is, as stated, connected with each shaft-carrying bar 78 of and for each record a similar organization, it will be understood that means for rotat- 70 ing the driven spur wheel 103 in each of the lower housings 83 will occasion the rotation of the selected record intended to be operated, through the rotation of said spur wheel 103 and all of its connected record 75 driving mechanism, and will not occasion the rotation of any other record of the assembled group of records.

The transmission mechanism.

Referring now more particularly to Figs. 8, 12, 13 and 14,—104 designates a traveling frame for supporting and carrying a novel and special gearing which, at the will of the operative, transmits power from the motor 85 to any selected driven spur wheel 103, to drive any selected record.

This frame is conveniently composed of a carrying base particularly designated by the numeral 104, which is right-angular of 90 the axis of the plurality of records and transverse of the casing, and which rests and travels upon rails 105 and 106, which extend longitudinally of the casing in parallelism with its front face, are mounted 95 within its lower compartment 4, and connected with vertically disposed end standards 107, which are pivotally mounted at 124 upon the upturned bracket ends 108 of a carrying bed plate 109 fixedly secured, 100 as convenience of manufacture may dictate, within said lower compartment of the casing and preferably in vertical planar alignment below the axis of the record shafts 86.

The traveling frame 104, which, as stated, 105 rests upon the rails 105, 106, bears against said rails by frame blocks 110, see Fig. 13, depending from its base.

111 designates side frames parallelly and vertically disposed with relation to the base 110 of the frame 104 and serving as supports for suitable bearings of a front stud shaft 112, upon which are fixedly mounted both a spur wheel 113, see Figs. 12 and 13, and a worm wheel 114 engaged with a worm 115 115 of a worm shaft 116, upon which shaft is mounted a typical governor 117 hereinafter more particularly referred to.

The spur wheel 113 engages with a spur pinion 118, Fig. 13, feathered upon a driv- 120 ing shaft 119 which extends longitudinally of the casing between the end standards 107 of the frame 104, in bearings 120 in which standards said shaft is mounted; and carries, feathered also upon it, a driving spur 125 wheel 121, preferably in hubbed connection with the spur pinion 118.

Assuming rotation imparted to the driv- 130 ing shaft 119, it is obvious that through the spur pinion 118, rotation will be imparted

to the spur wheel 113, see Fig. 12, and that the speed of rotation of said spur wheel will be governed by the dimensions of the teeth of the spur wheel 103 and those of the pinion 99, and the adjunctive gears.

Assuming, further, the desired rotation imparted to the driving shaft 119 and the driving spur wheel 121 feathered upon said shaft and rotating with it,—if, then, as is evident, said driving spur wheel 121 be engaged with any one of the driven spur wheels 103 on the stub shaft 101 in a lower housing of a record driving shaft 84, that shaft and in consequence its record will be rotated and driven.

The operation of the transmission mechanism.

Inasmuch as it is desired through the preferred transmitting mechanism under description, to be able to engage and drive any selected one of the driven spur wheels 103, it is obvious that it will be necessary to be able not only to move the traveling frame 104 which carries the above described transmitting mechanism endwise upon its rails, but also be able to throw or tilt the driving spur wheel 121 both out of and into toothed-contact with the selected driven spur wheel 103.

These two necessary movements I effect conveniently by the following means:—

122 designates what I term a frame-moving-bar connected at its upper end with the horn carrier 14 and extending diagonally downward and inward of the casing to a fixed connection at 125, see Fig. 8, with one of the side frames 111 of the traveling frame 104. Obviously, when by means of the operating handle 29, the horn carrier 14 is moved longitudinally of the casing through the fixed connection of this frame-moving-bar 122 extending from it to the traveling frame 104, the last-mentioned frame with its contained adjuncts will be moved longitudinally of the casing upon the rails 105, 106, so as to bring the driving spur wheel 121 into line in front of any one of the driven spur wheels 103.

In order to insure a contact between the driving spur wheel 121 and any one of the driven spur wheels 103 without risk to the teeth of said wheels, I find it advisable to be able to tilt the entire traveling frame, together, of course, with the rails upon which it travels and the end standards 107 to which said rails are connected, with reference to the pivots 124 on the upturned bracket ends 108 of the carrying bed plate 109, and this I conveniently accomplish by the following means:—

126 designates what I term a tilting arm, which is almost parallel with the frame-moving bar 122, as best seen in Fig. 8, and which at its lower end is connected by a

boxing 123, see Fig. 13, mounted on the driving shaft 119 and at its upper end is connected by a pivot 127 to the lower arm of a bell crank lever 128 pivoted at 129 to a bracket 130 extending from the horn carrier 14,—the bell crank lever 128 being at its upper end slotted at 131 to a connection at the lower end of a depending link 33, the upper end of which is connected at 32 to the inner end of the operating handle 29, see Figs. 3 and 6.

Obviously, the depression of the operating handle 29 will, through the link 33, occasion the lifting or upward pulling through the bell crank lever 128 of the tilting arm 126, and, consequently, through its connection by the boxing 123 with the driving shaft 119, the tilt of the traveling frame and all of its connective adjuncts with relation to the pivots 124 between the end standards 107 and the upturned bracket ends 108.

The connective mechanism from the motor.

In order to actuate the driving shaft 119 to effect through the connections already described in the traveling frame 104 the spur pinion 118 and the spur wheel 113, it is necessary to impart motion from a prime mover such as a motor or other motive device, to the driving shaft 119, and this I conveniently do through the connective mechanism particularly illustrated in Figs. 12 and 14, and of the following convenient construction:—

132 designates a countershaft, which I call a motor shaft, suitably housed in standards 133 connected with, or preferably components of, the bed plate 109, see Figs. 12 and 14, which through a belt or chain connection 134, see Fig. 8, from a sprocket or pulley 135, see Fig. 13, connects directly with a motor or prime mover of any character, not shown, but serving to impart rotation to said motor shaft 132.

Upon the motor shaft is mounted a driving spur wheel 136, which is in engagement with the driven spur wheel 137 on a stud shaft 138, upon which stud shaft is also mounted another driving spur wheel 139 in engagement with another driven spur wheel 140 on the driving shaft 119.

Obviously, through this connective gearing which is typical merely of a good form of gearing, the motion derived from the motor will be transmitted through the motor shaft 132 to the driving shaft 119, to the end of operating the transmission mechanism in the traveling frame.

The stopping mechanism.

When for the time being it is desired to stop the rotation of the driving shaft 119 in order to permit of the longitudinal movement of the traveling frame 104 and its adjuncts from one record driving mechanism 13,

to another, I find it convenient to utilize in connection with the governor 117 the following contrivance illustrated in Figs. 8, 13 and 16, namely:—

- 5 The disk head 141 of the governor, which is mounted to rotate with the worm shaft 116, see Fig. 13, is also adapted to have an end-for-end or transverse movement upon said worm shaft, and it is obvious that if 10 frictional pressure be exerted against the face of said disk head it will cause a stoppage of its rotation and consequently a stoppage of the operation of the worm and the train of gearing which imparts the desired 15 rotation to any one of the driven spur wheels 103.

This stoppage should, of course, be effected at the time when the traveling frame 104 is tilted so as to unmesh or disconnect the 20 teeth of a given driven spur wheel 103 and those of the driving spur wheel 121.

As already explained, this tilting is effected through the operating handle and its connections pulling upwardly on the tilting 25 arm 126, and the effect of the tilting is to cause the front edge of one of the side frames 111 to bear against the upturned end 142 of what I term a stop-crank-lever 143, which is pivoted at 144 conveniently to a lug 30 145 connected with the frame moving bar 122, as shown in Fig. 16.

The end of the crank lever opposite to its upturned end 142 is formed or provided with a friction stop 146 of leather or kindred substance, which, in the assemblage of the parts, normally stands at a distance from the disk head 141 of the governor, but in the tilting of the traveling frame is caused to contact with said disk head so as to stop 40 its rotary movement, which, as already explained, is due to the transmission gearing operated from the motor through the connective gearing upon its worm.

When, then, the entire transmission gearing is thus stopped, it is obvious that it will be easy to shift the traveling frame and its adjuncts in either direction longitudinally of the rails 105 and 106 and the driving shaft 119, and then by a further release 50 movement upon the operating handle, to make first the desired shift and then the desired re-tilting of the traveling frame 104 to make the desired new contact between the teeth of the driving spur wheel 121 and those of the driven spur wheel 103 of the driving mechanism of the selected record.

Having now described a construction conveniently embodying my invention, the operation of the elements—as successively described, will have been understood, and it will, therefore, be unnecessary to repeat how the entire organization may be operated to play any particular record.

In other words, it is sufficient to add that 65 when the selected plurality of records, de-

pending of course upon the dimensions of the machine as an entirety, has been put in place and the motor started to occasion through the connective mechanism, the rotation of the driving shaft and through it 70 and the transmission mechanism the operation of the record motive mechanism of a selected record,—the operator having through the operating handle 29, the swinging lever 37 and their adjuncts, placed the 75 transmitting mechanism in position to operate the desired record motive-mechanism and then locked the operating handle in proper position in the slot in the front of the casing,—the rotation of the selected record will occasion its playing until the record has been played and stopped itself, or at the will of the operative, the stopping devices have been thrown into action, or, if desired, the motor of the machine by any 80 preferred means itself been stopped.

In the sense, the operation of my present machine is in many regards similar to the operation of the machines of my patents referred to, differing materially, however, in 90 the fact already adverted to that only the record selected to be played is put into rotation to be played, while all of the other records of the group are standing still.

This is of course also true when the as- 95 semblage of records has been turned by the half turn of the circular record-carrying plate 6, as may be done when the records are double faced, in order to play first one face and then the other.

The novel and useful construction which I have illustrated and explained is well adapted to carry out the objects of my invention, but while the embodiment referred to is both desirable, inexpensive and satisfactory, it is to be understood that it is susceptible of modification in various details without departing from the spirit or scope of the invention or sacrificing any of its 105 advantages.

Having thus described my invention, what I claim as new and desire to secure by Letters Patent, is:—

1. In a sound-reproducing machine of the character described,—a group of independently operative revoluble records disposed in adjacent parallel planes upon a common axis of rotation,—a motive mechanism for operating any one of the records of the group independently of all of the 115 other records,—and a manual lever control extending externally of the casing for operating said motive mechanism.

2. In a sound-reproducing machine of the character described,—a group of independently operative revoluble records disposed in adjacent parallel planes and each in separate but removable adjustment upon a common axis of rotation,—means for securing the removable adjustment of each of 130

said records independently of the others,—a record-motive mechanism for operating any one of the records of the group independently of all of the other records,—and 5 a manual lever control extending externally of the casing and operative upon said record-motive mechanism.

3. In a sound-reproducing machine of the character described,—a group of independently operative revoluble records disposed in adjacent parallel planes and each in separate but removable adjustment upon a common axis of rotation,—means for securing the removable adjustment of each of 15 said records independently of the others,—a record-motive mechanism for operating any one of the records of the group independently of all of the other records,—a transmission mechanism operative upon the 20 foregoing record-motive mechanism,—a manual lever control extending externally of the casing which operates upon said transmission mechanism to both move it with relation to the foregoing record-motive 25 mechanism and to cause it to operate upon said mechanism.

4. In a sound-reproducing machine of the character described,—a group of independently operative and independently removable revoluble records disposed in adjacent parallel planes upon a common axis,—a numerically corresponding group of record motive mechanisms for operating each of the foregoing records independently of all of 35 the other records,—a transmission mechanism intervening the prime motive means of the talking machine and the record motive mechanisms for directly transmitting the operating movement of the prime motive 40 means of the machine to any record-motive mechanism,—a manual lever control extending externally of the casing and operative through the transmission mechanism upon any one of the foregoing record-motive 45 mechanisms,—and a prime motive means of any preferred character.

5. A sound-reproducing machine of the character described, which comprises in combination,—a casing,—a group of independently operative revoluble records disposed in adjacent parallel planes and in separate adjustment upon a coincident and common axis of rotation,—independently operative record-motive mechanisms for 55 occasioning the separate rotation of any one of the records of the group,—transmission mechanism common to all of them for operating said record-motive mechanisms,—a sound box common to all of the records of 60 the group,—a tone arm similarly common to all of the records of the group,—and a manual lever control extending externally of the casing and operative to both move and place the transmission mechanism in 65 such position as to operate with relation to

and upon a selected record-motive mechanism by placing the stylus of the sound box against the tone-grooved face of said selected record.

6. A sound-reproducing machine of the character described, which comprises in combination,—a casing,—a group of independently operative revoluble records disposed in adjacent parallel planes and in separate adjustment upon a coincident and common axis of rotation,—independently operative record-motive mechanisms for occasioning the separate rotation of any one of the records of the group,—transmission mechanism common to all of them for operating said motive mechanisms,—a sound box common to all of the records of the group,—a tone arm similarly common to all of the records of the group,—a manual lever control extending externally of the casing and comprising means (a) for placing the tone arm and sound box between any two of the group of records, (b) for moving the stylus into playing position and (c) for occasioning the operation of the mechanism which plays the selected record against the tone grooved face of which the sound box has been placed.

7. A sound-reproducing machine of the character described, which comprises in combination,—a casing,—a group of independently operative revoluble records disposed in adjacent parallel planes and in separate adjustment upon a coincident and common axis of rotation,—independently operative record-motive mechanism for occasioning the separate rotation of any one of the records of the group,—means controlled manually from the exterior of the casing for independently actuating any one 105 of said motive mechanisms to be operative upon a selected record of any one of the records of the group without operating upon any of the other records,—means for operating said controlled means,—and a sound box common to all of the records of the group.

8. A sound-reproducing machine of the character described, which comprises in combination,—a casing,—a group of independently operative revoluble records disposed in adjacent parallel planes and in separate adjustment upon a coincident and common axis of rotation,—independently operative record-motive mechanisms for occasioning the separate rotation of any one of the records of the group,—means for independently operating any one of said motive mechanisms,—a manual control extending externally of the casing and comprising an operating handle and a swinging lever which coöperate to both move and place said independently operative means in such a position as to occasion the separate operation of a selected record,—a sound box com- 125

tion to all of the records of the group,—a tone arm similarly common to all of the records of the group,—and connective means between the tone arm and the lever-control for both lifting and depressing the tone arm and for swinging it laterally in either direction.

9. A sound-reproducing machine, which comprises in combination,—a casing divided by a partition into an upper and a lower compartment,—a group of independently operative revoluble records disposed in adjacent parallel planes and in separate and removable adjustment upon a common axis of rotation,—means for occasioning the rotation of any one of said records independently of every other record,—and means operative manually from the exterior of the casing for controlling said motive mechanism whereby but one record at a time is rotated.

10. In a sound-reproducing machine, which comprises a casing, a group of independently revoluble records disposed in adjacent parallel planes and record-operating mechanism for operating any one of said records independently of the others,—a manually operated lever control comprising an operating handle and a swing lever,—separate mechanism connected with each record for occasioning its rotation,—a transmission mechanism operated by the lever control and adapted to be placed in position to operate upon any one of the record-operating mechanisms,—a prime motive mechanism,—and connective mechanism between said prime motive mechanism and said transmission mechanism.

11. A sound-reproducing machine of the character described, which comprises in combination,—a casing,—a group of independently operative revoluble records disposed in adjacent parallel planes and in separate adjustment upon a coincident and common axis of rotation,—a transmission mechanism,—independently operative record-motive mechanisms,—a connective mechanism between all of said motive mechanisms and said transmission mechanism,—a sound box common to all of the records of the group,—a tone arm similarly common to all of the records of the group,—and a manual lever control extending externally of the cabinet and operative upon the trans-

mission mechanism to place it in such position with relation to the record-motive mechanism of a selected record that the tone arm and sound box will be put into operative relation with reference to said selected record.

12. In a sound-reproducing machine of the character described,—a group of independently operative and independently removable records disposed in adjacent parallel planes upon a common axis,—a corresponding group of record-motive mechanisms operative respectively upon the respective records,—a prime motive mechanism for occasioning the operation of any one of the foregoing record-motive mechanisms,—a mechanism for directly transmitting the operative movement of said prime motive mechanism to any one of the record-motive mechanisms,—a manual lever control extending externally of the casing and operative through the transmission mechanism upon all of the foregoing record-motive mechanisms,—and a prime motive means of any preferred character.

13. In a sound-reproducing machine of the character described,—a group of independently operative and independently removable records disposed in adjacent parallel planes upon a common axis,—a corresponding group of record-clamping mechanisms which removably clamp each record independently of every other record,—a corresponding group of record motive mechanisms operative respectively upon the respective records,—a prime motive mechanism for occasioning the operation of any one of the foregoing record-motive mechanisms,—a mechanism for directly transmitting the operative movement of said prime motive mechanism to any one of the record-motive mechanisms,—a manual lever control extending externally of the casing and operative through the transmission mechanism upon all of the foregoing record-motive mechanisms,—and a prime motive means of any preferred character.

In testimony whereof I have hereunto signed my name this 10th day of December, A. D. 1919.

MAX KRAUSS.

In the presence of—

J. BONSALL TAYLOR,
C. D. McVAY.
